(57) **CLAIM**

The ornamental design for a sanitary pad, as shown and described.

DESCRIPTION

FIG. 1 is a perspective view of the invention;

FIG. 2 is a top plan view of the invention;

FIG. 3 is a rear end view of the invention;

FIG. 4 is a front end view of the invention;

FIG. 5 is a right side view of the invention;

FIG. 6 is a left side view of the invention; and,

FIG. 7 is a bottom plan view of the invention.

1 Claim, 5 Drawing Sheets
